J. RENNER

CHIMNEY CLEANER

Filed Sept. 26, 1922

Jos. Renner

By *A. B. Wilson & Co.*
Attorneys

UNITED STATES PATENT OFFICE.

JOSEPH RENNER, OF LAGRO, INDIANA.

CHIMNEY CLEANER.

Application filed September 26, 1922. Serial No. 590,730.

To all whom it may concern:

Be it known that I, JOSEPH RENNER, a citizen of the United States, residing at Lagro, in the county of Wabash and State of Indiana, have invented certain new and useful Improvements in Chimney Cleaners; and I do declare the following to be a full, clear, and exact description of the invention, such as will enable others skilled in the art to 10 which it appertains to make and use the same.

This invention relates to an improved chimney cleaner of the type permanently installed in place for automatically and continuously removing soot from the walls of the chimney.

The principal object of the invention is to provide a cleaner which is extremely simple and inexpensive, the same being such in 20 construction that it is capable of being placed in position for use by unskilled hands.

More specifically speaking, it is another object of the invention to provide a unique cleaner for chimneys embodying a bearing 25 supported on the chimney, there being a vertically disposed shaft rotatable in this bearing and the shaft carrying a wind vane or a blade, together with suitable cleaning means suspended from the shaft and depending into the chimney for removing the soot deposits when the shaft is set into rotation by the wind.

Inasmuch as the device is liable to be struck by lightning during storms, it is a 35 further object of the invention to associate means therewith for conveying the disastrous electrical current to the ground.

Furthermore, as it is desirable to render the device capable of being installed on different sizes and shapes of chimneys, the 40 proper details are adjustable to insure perfect and proper operation.

Other objects and advantages of the invention will be apparent during the course of 45 the following description.

In the accompanying drawings forming a part of this specification and in which like numerals are employed to designate like parts throughout the same:

50 Figure 1 is a central vertical sectional view through the upper portion of a chimney showing the cleaner arranged thereon, parts of the latter being shown in section to disclose the construction of the details more clearly.

Figures 2 and 3 are sections taken on the lines 2—2 and 3—3 respectively of Fig. 1.

Described in detail, the improved invention comprises a substantially square base 1 of suitable material such as concrete which 60 is adapted to be placed on the top of the chimney, this base being equipped with sockets 2 of insulation material which receive the lower ends of supporting rods 3. As is seen in the drawings, the upper ends 4 65 of these rods are directed laterally inward toward each other and are provided with closely spaced openings 5 through which a bearing sleeve 6 is adapted to extend. The sleeve may be threaded as shown to permit 70 nuts to be employed for connecting it with the laterally directed ends of said supporting arms. As before intimated, a vertical shaft 7 is rotatable and slidable in this bearing and the shaft has a blade or wind vane 75 8 rigidly secured to it for automatically setting it into rotation when the wind is blowing. For the purpose of retaining the shaft in different adjusted positions, a stop collar 9 is employed, the same engaging the upper 80 end of the aforesaid bearing sleeve. It is to be noted that the lower end of the shaft 7 extends beyond the corresponding end of the bearing sleeve and carries an adjustable cross head 10 composed of short arms 11 85 having spaced openings 12 for co-action with a flat-faced portion of the shaft. It is obvious that such a cross head is capable of being adjusted to render the device effective on different sizes of chimneys. The arms 11 90 carry depending chains 13 which in turn carry small chains 14, all of said chains depending into the chimney to be swept against the soot covered walls thereof for cleaning it when the shaft is set into rotation by the wind acting on the aforesaid vane. Cleaning elements of the chain type are not absolutely essential and it is understood that any suitable means may be substituted therefor in practice.

In order to prevent possible displacement of the structure from the chimney during strong wind storms, I provide a plurality of stay wires 15 which are connected at their upper ends to hooks 16 on the aforesaid supporting arms 3 and are nailed or otherwise secured at their opposite ends to the chimney.

It has already been intimated that an invention of the type specified is likely to 110

be struck by lightning during a storm and in order to safeguard the same against destruction from this source, suitable means is provided. In the drawings I have simply 5 illustrated a pointed spear 18 which is detachably connected with the upper threaded end 17 of the aforesaid rotary shaft. This spear is intended to conduct the electricity through it and down through the shaft or 10 possibly through the supporting arms 3. Hence, a ground wire 19 is connected with one of the arms for conveying the current down to the ground. While it may not be essential, it is preferred to insulate the 15 aforesaid hooks 16 from the supporting rods, to insulate the lower ends of the rods and to connect the aforesaid sweeping chains with the adjustable cross head through the medium of suitable insulated 20 balls or the like.

From the foregoing description it is obvious that when the wind is blowing, it will 25 strike the blade and as this is rigidly connected with the aforesaid vertical shaft, the latter will be set into rotation. Hence, the 30 chains which are associated therewith and depend into the interior of the chimney will be swept against the soot covered walls of the chimney to remove deposits of soot 35 therefrom. So long as a sufficient wind is blowing, the operation of the device is continuous and automatic.

Inasmuch as the chains 6 and 14 rotate rather rapidly when the wind is blowing 40 at a high velocity, it is obvious that as they contact the edge of the concrete base they will be subjected to severe wear. In order to reduce this wear and to prolong the life of the chains, I contemplate placing 45 balls 17 of suitable non-conducting material at these points. Hence, the balls will directly contact the base and the chains will be relieved of considerable wear.

By carefully considering the description 45 in connection with the drawings, persons familiar with devices of this class will doubtless be able to obtain a clear understanding of the invention. Therefore, a more lengthy and detailed description is 50 deemed unnecessary.

Since probably the best results may be obtained with the construction and arrange-

ment herein shown and described, this is taken as the preferred embodiment of the invention. However, I wish it to be understood that minor changes coming within the scope of the invention as claimed may be resorted to if desired. 55

I claim:

1. A chimney cleaner comprising a bearing, means for supporting the bearing in a position spaced above the top of the chimney, a vertically disposed shaft rotatable in the bearing and extended on opposite sides thereof, a wind vane secured rigidly to said shaft above the bearing for imparting rotation to the shaft, an adjustable cross-head secured to the portion of the shaft below said bearing, and a plurality of chains carried by and depending from 65 said cross-head into the chimney to remove the soot deposits from the inner faces of the walls thereof when said shaft is set into rotation. 70

2. A chimney cleaner comprising a base, a plurality of rods rising from the base and having their upper ends directed laterally inward toward each other, a bearing connected with the inner ends of said rods, a vertically disposed shaft rotatable in the 75 bearing, a wind vane rigidly secured to said shaft for imparting rotation thereto, a cross head connected with the lower end of the shaft, said cross head being composed of adjustable horizontally disposed 80 arms, and chains connected with said arms and depending into the chimney for removing the soot deposit from the inner walls thereof. 85

3. A chimney cleaner comprising a rotary 90 cleaning device including a plurality of comparatively light chains adapted to depend into the interior of the chimney to contact the inner surface of the walls thereof, wear-resisting devices carried by said chains and adapted to contact the edge of the opening of the chimney to prevent excessive wear of the chains, and means for supporting said cleaning device on the chimney. 95

In testimony whereof I have hereunto affixed my signature.

JOSEPH RENNER.
